Fig. 5.

A cross-sectional view of a cylindrical component, likely a piston or cylinder. The internal structure features several horizontal and vertical grooves and a central bore. Various features are labeled with numbers: 1, 2, 3, 4, 5, 6, 7, 8, 9, 10, 11, 12, 13, 14, 15, 16, 17, and 18. Label 1 is at the top, 2 is on the right side, 3 is on the left side, 4 is a central bore, 5 is a horizontal groove, 6 is a vertical slot, 7 is a vertical slot, 8 is a vertical slot, 9 is a vertical slot, 10 is a vertical slot, 11 is a vertical slot, 12 is a vertical slot, 13 is a vertical slot, 14 is a vertical slot, 15 is a vertical slot, 16 is a vertical slot, 17 is a vertical slot, and 18 is a vertical slot.

JOHN C. STRICKLER, OF SAN FRANCISCO, CALIFORNIA.

CAN-BODY MACHINE.

No. 888,202.

Specification of Letters Patent.

Patented May 19, 1908.

Application filed May 20, 1907. Serial No. 374,559.

To all whom it may concern:

Be it known that I, JOHN C. STRICKLER, a citizen of Switzerland, residing at San Francisco, in the county of San Francisco and State of California, have invented new and useful Improvements in Can-Body Machines, of which the following is a specification.

This invention relates to machines for making can bodies, the object of the invention being to provide a machine of this character by which the blanks for bodies are rolled into a cylindrical form and their edges are then immediately caused to snap into grooves or guideways, which confine said edges as the blanks are advanced by the machine; and a further object is to provide in such a machine improved means for moistening the edges of the blank with acid or other flux prior to soldering.

20 A further object of the invention is to provide such a machine which will be cheap and simple in construction and rapid and efficient in operation.

In the accompanying drawings, Figure 1 is a side view of the machine; Fig. 2 is a plan view of the same; Fig. 3 is a perspective view of the sizing shell and body guard; Fig. 4 is a similar view of the former; Fig. 5 is an end view; Figs. 6, 7, 8, 9, are transverse sections 30 on the lines 6—6, 7—7, 8—8, 9—9, respectively of Fig. 2; Fig. 10 is an enlarged detail of the seaming dies; Fig. 11 is a broken vertical sectional view of one of the cams.

Referring to the drawings, 1 indicates a suitable frame, formed at the top with a channel way 2, for an endless carrier 3, said carrier traveling around hexagonal rollers 4, 5, the roller 4 at the front end being mounted on a shaft 6 and being intermittently advanced by means of a wheel 7, having formed therein six deep radial recesses 8, said wheel being adjustably secured, by bolts 9 passing through slots 10, to a plate or disk 11 which is mounted on said shaft 6. The recesses 8 are adapted to be engaged in turn by one or the other of a pair of rollers 12, mounted diametrically opposite to each other on the outside of a gear wheel 13 on a stud shaft 14 driven by a pinion 15 on a shaft 16 driven by 45 a pulley 17 from any suitable source of power. By this means, from the continuous rotary motion of the shaft 16 an intermittent rotary motion is given to the shaft 6 and an intermittent advance to the endless carrier. 50 The blanks for the can bodies are fed transversely to the machine by means of a

guideway 18 having walls 19, and secured to brackets 27 mounted on the frame of the machine, by which guideway said blanks are caused to pass upper and lower plates 20, 21, 60 the upper plate 20 being secured by screws 22 to an angle plate 23, secured adjustably as to its vertical position to a longitudinal block 24 secured at its ends to two arms 25 pivoted at 28 on the brackets 27. By this means said block and the parts attached thereto can be swung upwards and to one side to expose the parts below the same. The lower plate 21 forms one side of a former or guide piece 29, which is secured by screws 70 30 to a die bar 31, said bar extending the length of the machine and serving to support at suitable intervals the parts for operating upon the can body. The transverse members 32 of each link 28 of the carrier is formed with a central recess 33 adapted to receive said bar, so that said member moves along the machine in contact with said bar. The blank having been guided between said upper and lower plates 20, 21, is then directed 75 between two horizontal rollers 34, 35, the upper roller 34 being mounted in the swinging arms 25 which support the block 24 and the lower roller 35 being mounted in the brackets 27 upon which said arms are pivoted. Said rollers are both positively driven by means of gear wheels 36, 37, which mesh with each other, the lower gear wheel 37 being on a shaft 38 carrying a pinion 39 driven by a gear wheel 40 on the cam shaft 41, having 80 thereon a bevel gear 42 driven by a bevel gear 43 on the main driving shaft 16. This arrangement permits the two rollers to be positively driven while at the same time the upper roll can be readily raised with the 85 swinging arms. The blanks are given a slight concave curvature downwards by reason of the direction in which they are passed between said rollers 34, 35, and said curvature is increased by said blanks being forced by 90 the rollers against the underside of a sloping plate 45, which is secured to an angle plate 46, adjustably secured by means of screws 47 through slots therein to the block 24. The blank being given in this way a concave 95 100 curvature the front edge thereof is passed down in the link 28, past the rounded surface of the former piece 29, and within the concave or trough-shaped body-guard 48, which is curved so as to confine the advancing edge of the blank and direct it against the underside of the lower plate. The guide 105 110

piece of which said lower plate forms a part is made with two oppositely disposed half-rounded grooves 49, 50, the upper groove 49 being adapted to receive the rear edge of the blank and the lower groove 50 to receive the front edge thereof. These grooves form an important part of my invention. When the front edge of the blank is directed upwards it is forced into the lower groove 50 and the 10 spring of the metal of the rear edge, as it leaves the rollers 34, 35, causes said rear edge to spring into the upper groove 49.

The can body has now been bent into a substantially cylindrical form, with its edges 15 in the grooves 49, 50. These grooves are supplied with acid from an acid reservoir 54, from which reservoir conduits 55 lead to cavities 56 formed in the lower plate and in the guide plate, from which cavities the acid 20 is fed by small conduits 57 to the grooves 49, 50. By this means said grooves are kept supplied with acids, and thereby the edges of the blanks are moistened with acid and brightened for soldering. These conduits 25 enter said grooves at the front ends, the object of this arrangement being to insure that the front or advancing ends of the edges of the blank are moistened with the acid or other flux, and it is thereby also insured that 30 the whole length of each edge is so moistened, since it is necessary for the whole of said edge to pass through the front portion of the groove in its movement in the machine. It will be observed that the entrance into each 35 groove for the edge of the can body blank is by means of comparatively narrow interstices or slits; this insures that a sufficient quantity of acid will be contained within the groove, and that the space within said groove 40 shall be sufficiently larger than the space occupied by the edge of the blank, and it also prevents the escape of the acid from the groove both when the edge of the blank is inserted thereinto, and when the entrance to 45 the groove is unobstructed. The blank is now advanced by the intermittent motion of the carrier to the next part of the machine, which is particularly shown in Figs. 7 and 10. In so doing the groove 50 in the former guides 50 the lower or front edge of the blank into a groove 58 in a die 59, said die having formed therein, immediately below said groove, a recess 60. At the same time the groove 49 in the former guides the upper or rear edge over 55 the upper surface of said die and into a groove, 61, formed in a plate 62 adjustably secured to a head 63 secured upon the upper end of a cam lever 64 which is actuated by a cam 65 on the cam shaft 41. By the operation 60 of this cam, said plate 62 is caused to descend, which has the effect of forcing the rear edge of the blank down past a shoulder 66 on the die, thereby making a hook-shaped bend in said edge, and at the same time a 65 tongue 67 formed on said plate 62 bears

against the lower edge of the blank and forces it into the recess 60, thereby forming a hook-shaped bend in this edge also.

The tongue 67 is substantially in contact with the shoulder 66 only at the front or advancing portion thereof, the rear portion of the tongue being more remote from the shoulder. The object of this construction is to leave room for the edge of the blank between the recessed portion of said tongue and 75 said shoulder. Upon the outer side of the plate 62 is secured a guide 97, the purpose of which is to give a sharp edge to the hook formed over the shoulder 66.

68 indicates a shell, the function of which 80 is to completely fill the can body at the time of locking and uniting its edges. It is supported by inwardly extending flanges 69 of the shell resting on shoulders 70 formed on the transverse members of the carrier, and is 85 secured against longitudinal movement by its rear end being secured, as shown in Fig. 3, to the body-guard 48. The shell is reduced in diameter beneath the rollers for bending the blank for two reasons, first, in order that 90 the can blank may move freely along the shell at the point where it is not necessary to completely fill the cylinder formed by the blank, and, secondly, this portion of the shell is not intended to be removed, and is always maintained in position notwithstanding the fact 95 that various sizes of can bodies are made upon the machine. Around said shell, beneath the part of the machine where the locking of the edges of the can body is to be effected, is a shell section 72, which is normally pressed close to the shell 71 by means of coiled springs 73 around screws 74 screwed into the shell 71, said springs being compressed between said shell 71 and the heads 100 of said screws. Upon the upwardly facing edges of the shell section 72 are formed humps 75 spaced apart the distance between two adjacent transverse members 32 of the carrier. The parts are so arranged that, at 105 the time the locking is effected, two transverse members of the carrier are on these humps, thereby forcing the shell section downwards or outwards against the action of said springs, the effect being to completely 110 fill the can body, and hold it in the best position for effecting the junction of the hook-shaped edges of said body. When the transverse members of the links pass onwards, 115 said humps are released therefrom, and the shell section moves upward under the action of the springs.

The can body thus filled out is pressed down upon a bumping plate 76 in which is a 120 groove 87 for receiving the hooks on the edges of the blanks for seaming, and which is recessed at the middle of its under side, as shown at 77, and is supported only at its outer edges on the links of the carrier, the 125 effect of this being to transmit the pressure 130

of the bumper to said links at points as near as possible to the supports for the links, thereby permitting said links to be made as light as possible, while capable of withstand-
ing the pressure of the bumper. The pres-
sure on the can body is produced by means of
plates 79, which are movably held to a block
80 suspended by rods 81 from a lever 82, said
plates being depressed by means of springs
83 around said rods. Thus said plates exert
a constant pressure upon the can body or
blank, and hold it down to the former, there-
by, with the former, acting as a brake against
the movement of the carrier and insuring
that both edges of the blank register with
each other as to their longitudinal and trans-
verse positions. The hook-shaped edges of
the blank being now in position, engaging
each other, the cam lever 82 is actuated by
its cam 85, thereby depressing the bumping
block 80, which presses the two edges to-
gether. By pivoting the cam levers 64 and
82 at the side of the machine, and to one side
of the channel 2, so that the levers extend
over the channel, and the devices carried
thereby successively operate on a can body
advanced in said channel, it is possible to in-
spect at all times the can bodies as they pass
along, and also the die and bumper plate co-
operating with the devices carried by the
levers. The can is now advanced to the pos-
ition where it is soldered, and the seam of the
can body passes beneath the soldering iron
and then beneath the valve through which
the solder drops. Then for greater certainty
it passes beneath a second soldering iron and
is then again supplied with solder. The can
body is then discharged from the machine.
The function of the guidepiece 29 is to guide
the advancing edge of the blank into the
space between the shell and the outer body-
guard 48.

I claim:—

1. In a can body machine, the combina-
tion, with upper and lower rollers, means for
guiding a can body blank therebetween and
a plate arranged to deflect and curve a can
body blank passing through said rollers, of a
guide having grooves arranged to receive the
front and rear edges of the can body blank,
said guide being provided with an under sur-
face adapted to guide the advancing edge of
the can body blank into one of said grooves
as said blank leaves said rollers, having also
a groove arranged beneath the lower roller,
and having surfaces adapted to guide the
rear edge of the blank into said latter groove
as the blank leaves the rollers, substantially
as described.
2. A can body machine, comprising upper
and lower rollers means for guiding the blank
between said rollers, and a plate arranged to
deflect and curve a can body passing through
said rollers and a guide having formed there-
in upper and lower grooves, and having a

surface arranged to guide the front or ad-
vancing edge of the blank into the lower
groove, the upper groove being arranged be-
neath the lower roller, said rollers and the
guiding means for the blank being so con-
formed as to impart to said blank a curva-
ture sufficient to cause its rear edge to spring
into said upper groove upon leaving the
guiding means, substantially as described. 70

3. In a can body machine, in combination
with upper and lower rollers a plate arranged
to deflect and curve a can body blank passing
through said rollers for bending a blank, a
guide having integral therewith a lower guid-
ing plate for guiding the blank to the rollers,
said guide having therein a groove to receive
the front or advancing edge of the can body
blank, and the guide plate having a groove
to receive the rear edge of said blank, sub-
stantially as described. 75 80

4. In a can body machine, the combina-
tion, with means for bending a can body
blank into an approximately cylindrical
form, of an element formed with grooves to
receive respectively the adjacent parallel
edges only of said blank when so bent, a res-
ervoir for a flux, and conduits leading from
said reservoir to said grooves, substantially
as described. 85 90

5. In a can body machine, the combina-
tion, with means for bending a can body
blank into an approximately cylindrical form,
of an element formed with grooves to receive
respectively the adjacent parallel edges only
of said blank, a reservoir for a flux, and con-
duits leading from said reservoir to the front
ends of said grooves, substantially as de-
scribed. 95 100

6. In a can body machine, the combina-
tion, with means for bending a can body
blank, of an element formed with grooves to
receive the edges of said blank when so bent,
a reservoir for a flux, and conduits leading
from said reservoir to said grooves, said
grooves having comparatively narrow in-
terstices for the passage of the blank edges
thereinto, substantially as described. 105 110

7. In a can body machine, the combina-
tion of a longitudinal die for an edge of a can
body blank, having a fixed groove for the ex-
treme edge of said blank, and a fixed recess
arranged to underlie the edge of the blank
entering said groove, said die also having a
shoulder, and a plate having a recess adapted
to receive the other edge of the blank, and
having a tongue adapted to enter the first
named recess, and means for suitably mov-
ing said plate, to cause said tongue and sec-
ond named recess to move in unison, the
tongue to enter said recess, and to cause the
recess to pass said shoulder, substantially as
described. 115 120

8. In a can body machine the combina-
tion of a die having a shoulder, a plate having
a tongue adjacent to said shoulder, and 125
130

means for moving said plate so that the tongue enters said die, the lower or advancing portion of said tongue being arranged to be substantially in contact with said shoulder while the plate is so moved, while the upper or rear part of the tongue is more remote therefrom.

9. In a can body machine, the combination with the die having a groove and a recess beneath said groove and having also a shoulder, of a plate movable adjacent to said shoulder, and a former having grooves for the edges of the blank, one of said grooves being arranged to guide said edge into the groove 15 of the die, substantially as described.

10. In a can body machine, the combination with rollers for bending the blank, and a die and plate for forming the hooks of said blank, of a shell having an enlarged portion 20 beneath said die to fill the blank and a portion reduced in diameter beneath said rollers around which the blank is bent, a carrier for advancing the blank, and means for securing the shell against the movement of said carrier, 25 substantially as described.

11. In a can body machine, the combination of links forming an endless carrier, rollers and co-acting device for bending the can body blank, and means for intermittently 30 advancing the carrier, said means being so arranged that each link in turn is brought beneath said rollers, said links being open to permit the can body blanks to be bent and to pass into said links in succession, substantially as described.

12. In a can body machine, the combination of links forming an endless carrier, rollers and co-acting device for bending the can body, and means for intermittently advancing the carrier, said means being so arranged that each link in turn is brought beneath said rollers, said links being open to permit the can body blanks to be bent and to pass into said links in succession, and stationary inner and outer parts for suitably 45 guiding each blank so bent within a link, substantially as described.

13. In a can body machine, in combination with a suitable bumping plate for the 50 can body blank, a bumping device for securing together the hook-shaped edges of the blank, comprising a block and means for

reciprocating said block to and from said bumping plate, side plates slidably secured upon the block, and springs for normally depressing said side plates upon the bumping plate, whereby said side plates also act as brakes to control the advance of the blank, substantially as described.

14. In a can body machine, in combination with a bumping device for securing together the hooked edges of the can body blank, links forming an endless carrier and having transverse members, and a bumping plate supporting the can body blank, while 65 being so bumped, said plate resting at its edges only upon said transverse members, substantially as described.

15. In a can body machine, the combination of a bumper for uniting the hook-shaped 70 edges of a can body, links forming an endless carrier for advancing the can body, a shell section suitably arranged relatively to said bumper, and springs for normally contracting said shell section, said section being 75 formed with humps adapted to be engaged by said links as the latter advance to expand said shell section against the action of said springs, substantially as described.

16. In a can body machine, the combination of links forming an endless carrier, and means for supporting the same, and a bumping plate supported directly on the links, substantially as described.

17. In a can body machine, the combination of links forming an endless carrier, and means for supporting the same, a bumping plate supported directly on the links, and a sizing shell suspended from the links, substantially as described.

18. In a can body machine, the combination with links forming an endless carrier, of a die bar supported by said links, a guide piece, a die, a bumping plate, and a soldering plate secured in the order named on said die bar, and devices respectively co-acting with 95 said members so secured.

In testimony whereof I have hereunto set my hand in the presence of two subscribing witnesses.

JOHN C. STRICKLER.
